UNITED STATES PATENT OFFICE.

WILLIAM S. OSBORNE, OF HYDE PARK, MASSACHUSETTS, ASSIGNOR OF ONE-HAIF TO B. F. STURTEVANT COMPANY, OF BOSTON, MASSACHUSETTS, A CORPORATION OF MASSACHUSETTS.

SEPARATOR FOR FIBROUS MATERIALS.

No. 853,518.

Specification of Letters Patent.

Patented May 14, 1907.

Application filed February 1, 1906. Serial No. 298,898.

To all whom it may concern:

Be it known that I, WILLIAM S. OSBORNE, a citizen of the United States, residing at Hyde Park, in the county of Norfolk and State of Massachusetts, have invented certain new and useful Improvements in Separators for Fibrous Materials; and I do hereby declare the following to be a full, clear, and exact description of the invention, such as will enable others skilled in the art to which it appertains to make and use the same.

The present invention relates to an improvement in separators for fibrous materials.

15 The object of the invention is to produce a separator to operate upon comminuted fibrous materials such as ground charcoal and talc, in which shreds or flakes of a fibrous character are mingled with powdered or disintegrated matter, the machine being adapted to separate the powder from the fibers or flakes, and the invention consists in the improved separator hereinafter described, as defined in the claims.

25 In the drawings Figure 1 is a front elevation of a separator embodying the present invention with part of the casing broken away, Fig. 2 a side elevation partly in section, and Fig. 3 is a sectional plan.

30 The separator consists generally of an outer casing surrounding a rotary cylindrical screen. The comminuted material is fed into the rotary screen and the separation takes place therein, the powdery portion of 35 the material passing out laterally through the screen and the fibrous or flaky portion of the material being arrested by, and falling from the open end of the screen, being discharged through a separate opening.

40 The casing comprises a prismatic upper portion 1, and a pyramidal portion 2 extending from the lower end thereof and provided with an outlet 3. The top 4 of the casing 1 is closed except at the center, where the inlet 45 for the material and air is located. The air is introduced in a diagonal direction through a trunk 5 mounted upon the top 4 of the casing. The material is admitted to the air trunk through a pipe 6 which leads through 50 the side of the air trunk and projects the material toward the center of the air blast. The rotary cylindrical screen 7 is open at the top and bottom and is supported upon arms 8

fixed to the shaft 9 by which the screen is actuated. The screen shaft 9 is mounted in a bearing 10 supported on the trunk 5 and a step bearing 11 carried by a cross bar 12 near the bottom of the prismatic portion 1 of the casing. The upper end of the screen shaft 9 carries a bevel gear 13 which meshes with a gear 14 carried by a shaft 15 supported in bearings 16 on the top of the trunk 5, which shaft 15 carries upon one end a cone pulley 17 by which the screen may be driven at various speeds for the purposes hereinafter described. One-half of the peripheral surface of the rotary screen is embraced by a suction hood 18 which constitutes a receptacle for the powdered part of the material and leads to the discharge passage 19 to which the eye 70 of an exhaust fan (not shown) is attached. By means of a small pipe 20 a part of the air is conducted to the exterior of the screen for a purpose hereinafter set forth.

The operation of the machine is as follows:—The material to be separated flows into the air trunk 5 through the pipe 6 and is discharged with the entering air into the center of the rotary screen. The arms 8 of the screen, striking the material as it enters, distribute it throughout the screen evenly and tend to prevent the material from finding its way in a mass to the inner surface of the screen. The fibrous or flaky portions of the material fall down through the screen into the pyramidal portion of the casing whence they are discharged through the outlet 3, while the finer portions of the material pass through the screen and are discharged with the air through the outlet 19. In general, the material which falls into the screen, as it takes up a rotary motion therefrom, centrifugates to the surface of the screen, moving more largely in the direction of the hood 18 and outlet 19 than in other directions. The particles of material which do not pass through the screen into the hood tend to clog the screen at this point but the screen operates to clear itself of such deposits because as soon as that portion of the screen moves away from the hood, the direction of the air passing through the screen is reversed, owing to the air flowing through the pipe 20, and the particles previously held against the walls of the screen, by the pressure on the outside, are released and fall from the screen.

The material thus loosened from the walls of the screen is now subjected to a repetition of the separating process, the fibrous and flaky particles falling through the bottom of the screen, and the lighter particles passing through the screen into the hood. The screen as shown consists of woven wire with an elongated mesh; that is, the mesh of the screen is longer in the direction of the periphery of the cylinder than in the direction of an element thereof. This arrangement has been chosen because it contributes to the efficient separation of the different kinds of fibrous materials from each other. It is also believed that the efficient openings in the screen through which particles pass, is dependent upon the speed of the rotation of the screen. Thus when the speed is increased the effect is to reduce the efficient area of the mesh openings. This fact has been availed of to secure the means of regulating the fineness of material permitted to be discharged through the screen and through the outlet 19. By placing a driving belt upon a smaller one of the pulleys 17, the speed of the screen will be increased.

The particular form of apparatus illustrated and described herein has been used in the separation of the fibrous portions of ground charcoal from the powdery portion, and is useful in connection with any material which is reduced, by grinding to a mixture of fibrous or flaky particles and powder, where the difference in specific gravity between the large and small particles is not great. The problem which the inventor has endeavored to solve by this machine has been the separation of materials very closely approximating each other in the capacity to be supported by a current of air. Thus the fine dust and fibrous portions of ground charcoal closely approximate each other in the capacity to be supported by a current of air, and the difficulty has been to separate the two from each other, centrifugal separators having been found incapable of separating efficiently substances of this character.

One of the features of the invention which it is considered contributes most markedly

to its success with such materials resides in the repeated projections of the material against the walls of the screen.

The invention is not limited to the illustrated embodiment but may be embodied in other and different forms within the scope of the following claims.

Having now described the invention what is claimed is:—

1. A separator for fibrous material having, in combination, a vertical cylindrical screen, means for rotating the screen, a casing surrounding the screen and provided with an air outlet embracing a portion only of the screen, means for delivering material and a current of air to the upper end of the screen, and a receptacle for material falling to the bottom of the screen, substantially as described.

2. A separator for fibrous materials having, in combination, a vertical cylindrical screen, means for rotating the screen, a casing surrounding the screen and provided with a lateral air outlet embracing a portion only of the screen, and means for introducing air and material into the screen, substantially as described.

3. A separator for fibrous materials, having in combination, a vertical cylindrical screen provided with meshes elongated horizontally, means for rotating the screen, a casing surrounding the screen and provided with an air outlet embracing a portion only of the screen, and means for delivering material and a current of air to the interior of the screen, substantially as described.

4. A separator for fibrous materials, having in combination, a rotary screen provided with a mesh elongated in its direction of rotation, means for causing a current of air to flow through a portion of the screen, means for introducing material to the air current, and means for rotating the screen at variable speeds, substantially as described.

In testimony whereof I affix my signature, in presence of two witnesses.

WILLIAM S. OSBORNE.
